UNITED STATES PATENT OFFICE.

EDWARD O. KEATOR, OF CINCINNATI, OHIO.

HANGER FOR TEMPORARY GIRDER AND BEAM FORMS.

1,237,525.

Specification of Letters Patent. Patented Aug. 21, 1917.

Application filed February 3, 1917. Serial No. 146,316.

To all whom it may concern:

Be it known that I, EDWARD O. KEATOR, a citizen of the United States of America, and resident of Cincinnati, in the county of 5 Hamilton and State of Ohio, have invented a new and useful Improvement in Hangers for Temporary Girder and Beam Forms, of which the following is a specification.

An object of my invention is to produce 10 an improved beam or girder form hanger for the temporary form work of concrete incased steel structures.

A further object is to produce a beam or girder form hanger for the temporary 15 form work of concrete incased steel structures, which will secure the form in position to receive concrete and which will space it properly with relation to the steel beam or girder to be incased, simultaneously 20 with the securing operation.

These and other objects are attained in the hanger described in the following specification and illustrated in the accompanying drawings, in which;

25 Figure 1 is a perspective side view of a hanger embodying my invention.

Fig. 2 is a perspective end view of the hanger illustrated in Fig. 1.

Fig. 3 is a transverse sectional view of a 30 concrete incased steel beam or girder having my improved form hangers in position and supporting temporary form work employed in the concrete incasing operation, certain details of the hanger being omitted in this 35 view.

My improved form is designed to be attached to the lower flanges of structural steel members, such as I-beams, which are usually employed in such structures for 40 girder and beam purposes. The hanger embodying my invention consists of a U-shaped clamp member 4 adapted to receive one flange of the I-beam, as disclosed in Fig. 3, the upper portion of the clamp being provided with a serrated inclined surface 5 adapted to engage the upper surface of a lower flange of the I-beam. Immediately below this serrated surface a lug 6 is formed, this lug being internally screw 45 threaded to receive the screw threads of a bolt 7 the upper end of which is adapted to be brought into clamping engagement with the end surface of the I-beam. A web 8 is formed on the clamp member for the 50 purpose of strengthening it as well as lightening it. In Figs. 1 and 2 I have shown my

improved hanger as having a hook 15 formed thereon for the purpose of receiving a wire adapted to pass between hangers on opposite sides of an I-beam supporting 60 them, for the purpose of keeping them in position should the bolts 7 be accidentally loosened. The hooks are omitted in the construction disclosed in Fig. 3.

In using my improved hanger the heads 65 of the bolts are employed for supporting the temporary form work to mold the concrete around the I-beam and the length of the bolts is such as to permit of sufficient concrete occupying the space between the 70 flanges 9 with which the hangers coöperate, and the lower board 10 of the temporary form work. In the usual temporary form work, battens 11 are employed for supporting the lower board 10 as well as the side 75 boards 12 of the form. In addition to this the floor slab forming boards 13 are supported from the side boards 12, so that the weight of the entire temporary structure, as well as the liquid concrete contained therein, 80 is supported by the bolts 7. In order to vary the thickness of concrete surrounding the I-beam it is merely necessary to change the lengths of the bolts with which the hangers are secured to the lower flanges of 85 the I-beam, thereby bringing the heads 14 of the bolts at a greater or less distance from the I-beam, as desired.

In dismantling the form work supported by my improved form work hanger, the 90 bolts 7 are unscrewed from the clamp members 4 and from the hardened concrete surrounding their screw threaded ends. This leaves the form work in condition to be removed from adherence with the concrete 95 incasing the structural steel member. Because of the concrete having hardened around the clamp members 4, these members are left embedded therein. The openings left after removal of the bolts, may be closed 100 with plugs or they may be left for the reception of bolts or hangers employed for supporting pipes and similar fixtures.

Having thus described my invention, what I claim is:

1. In combination with a temporary beam or girder form for structural steel beams or girders to be incased with concrete, a hanger comprising a U-shaped clamp member adapted to receive between its branches a 110 flange of the structural steel member to be incased, with the upper surface of the

22

flange in engagement with the upper branch thereof, and a headed bolt of predetermined length, mounted in the lower branch of the clamp member, adapted to secure the clamp member to the flange to support a form in engagement with the head of the bolt and in spaced relation to the structural steel member by being brought into engagement with the under surface of the flange.

10 2. In combination with a temporary beam or girder form for structural beam or steel girders to be incased in concrete, a hanger comprising a U-shaped clamp member having one of its branches adapted to engage 15 a flange of the structural steel member, a lug formed on the opposite branch and having an interiorly screw threaded passage

adapted to receive the screw threads of a bolt, a headed bolt of predetermined length located in the passage and adapted to have its end brought into engagement with the flange to clamp a flange of the structural steel member between it and the coöperating branch of the clamp member, the head of said bolt being adapted to support the temporary form work in spaced relation to said structural steel member.

In testimony whereof, I have hereunto subscribed my name this 29 day of January, 1917.

EDWARD O. KEATOR.
